Attorney

UNITED STATES PATENT OFFICE.

HENRY M. SHEER, OF QUINCY, ILLINOIS, ASSIGNOR TO H. M. SHEER COMPANY, OF QUINCY, ILLINOIS, A CORPORATION OF ILLINOIS.

HEATING SYSTEM FOR INCUBATORS, BROODERS, AND THE LIKE.

Application filed September 25, 1922. Serial No. 590,461.

To all whom it may concern:

Be it known that I, HENRY M. SHEER, a citizen of the United States, residing at Quincy, in the county of Adams and State 5 of Illinois, have invented certain new and useful Improvements in Heating Systems for Incubators, Brooders, and the like, of which the following is a specification.

This invention relates to heating systems 10 for incubators, brooders, and the like, and the object of the invention is to so construct the valve mechanism that it may be controlled automatically by the temperature within the device being heated.

15 A further object is to arrange the valve directly beneath the burner where the oil is always kept at approximately the same temperature causing the flow of oil to remain more uniform than is the case when 20 the temperature of the oil varies.

The drawing discloses a longitudinal section through the burner, feed-tank and feed-pipe.

The letter A indicates the supply tank; 25 B, a receptacle or lower reservoir; C, a base for the support of the two; and D, a burner. The numeral 1 indicates a feed-pipe leading horizontally from the base C, the outer end thereof being provided with an elbow 30 2, connected by a nipple 3 to the burner D. A valve-seat 4 is arranged in the extreme outer end of the pipe 1 directly beneath the burner, and arranged concentrically of the feed-pipe 1 is a valve stem 5 made of a 35 metal or material sensitive to heat or cold, causing the stem to expand or contract with a varying temperature of the oil in the pipe. The latter is effected by the temperature beneath the canopy (not shown).

40 The outer end of the valve-stem 5 is pref-

erably screw-threaded as at 6, having secured thereto an actuating-lever 7. A screw-threaded plug 8 is received in the open end of the base C, being provided with a threaded base 9 to receive the threaded end of the 45 stem 5. Spaced from the inner end of the plug is a washer 10 having interposed therebetween suitable packing means 11 to prevent possible leakage of oil.

It will thus be seen that I have constructed a thermostatic valve which may be manually actuated or automatically actuated by the heat generated beneath the canopy, insuring an even control of oil being fed 50 to the burner.

I claim:

1. A heating system including a supply tank, a burner, a base for supporting the tank, said base having a channel extending therethrough, and communicating with the 60 tank, a feed pipe connecting the channel and burner, a plug screwed into one end of the channel in the base and having a screw threaded opening therethrough, and a valve- 65 stem screwed into said opening for controlling the supply of oil to the burner.

2. A heating system comprising a supply tank, a burner, a base for supporting the tank, said base having a channel therethrough and communicating with the tank, 70 a feed pipe communicating with the channel and burner and having a valve seat therein, a plug screwed into the base and having a screw-threaded opening therethrough, a valve stem screwed into said opening, and 75 packing interposed between the end of the plug and the channel.

In testimony whereof I affix my signature.

HENRY M. SHEER.
